FIREPLACE

Charles J. Richter and Jacob F. Richter, Long Island City, N. Y., assignors to Charles W. Richter & Sons, New York, N. Y., a copartnership composed of Charles J. Richter, Charles W. Richter and Jacob F. Richter

Application January 30, 1932. Serial No. 589,874

17 Claims. (Cl. 20—73)

An object of the invention is to provide an inexpensive fireplace which is strong and durable in construction and which is attractive in appearance.

Another object of the invention is to provide a fireplace for use with an electrical device representing burning logs, or with a similar device, the fireplace being pressed out of metal and having the appearance of a fireplace manufactured of brick, stone, or other similar material.

The invention comprehends a fireplace which has a front which may be pressed and be painted as desired to represent brick, stone, or other similar material, the front having an inwardly disposed portion to form the sides and back of a fireplace opening, a member being secured to the rear of the front and to the top of the sides and the back of the inwardly disposed portion forming the fireplace opening to form the top of the fireplace opening, the member being continued beyond the sides of the fireplace opening and being secured to the rearwardly extending portions at the sides of the front of the fireplace, the said member serving to brace the sides and the back of the inwardly disposed portion forming the fireplace opening.

The invention also comprehends a fireplace having a mantel with a recess extending at its front and sides and which is disposed at the top and the rearwardly extending sides of the fireplace, the fireplace, the mantel and a chimney extending upwardly from the mantel being braced and being secured in a manner to obtain great strength and durability, while making it possible to manufacture the fireplace together with the mantel and chimney at little cost. In the preferred form of the construction, a base is provided to which the front of the fireplace is secured, as well as the inwardly disposed portion and the sides of the front of the fireplace.

Additional objects of the invention will appear in the following specification in which the preferred form of the invention is described.

In the drawings similar reference characters refer to similar parts in all the views, of which

Figure 1 is a front elevation showing the fireplace with its chimney,

Figure 2 is a rear elevation of Figure 1,

Figure 3 is an enlarged sectional elevation on the line 3—3 of Figure 2,

Figure 4 is a sectional view on the line 4—4 of Figure 3, but on the scale shown in Figures 1 and 2,

Figure 5 is a sectional view on the line 5—5

of Figure 3, but on the scale shown in Figures 1 and 2, and

Figure 6 is a sectional view on the line 6—6 of Figure 3, but on the scale shown in Figures 1 and 2.

By referring to the drawings it will be seen that a fireplace is provided which is pressed out of sheet metal and is reinforced for strength and durability, the fireplace being provided for use in connection with electrical devices which, when lit, represent burning logs. The fireplace has a front member 10 having its sides 11 bent rearwardly and with the rear edges 12 of its side bent substantially parallel with its front member 10. The rear of the sides 11, at their bottom, are cut away at 12' to accommodate a moulding at the bottom of the wall against which the fireplace is to be disposed. The front member 10 has a fireplace opening 13, an inwardly disposed portion or portions forming the sides 14 and the back 15 of the fireplace opening. It will be understood that the sides and back of the fireplace opening, with which the front member 10 is provided, may be manufactured of separate pieces of sheet metal which may be welded or soldered together to form the sides and the back of the fireplace opening as illustrated in the drawings. The front member 10, together with the sides 14 and the back 15 of the fireplace opening, and also with the sides 11 of the front member 10, are secured to the top of a base 16 by welding, soldering, or other means, the base 16 having a periphery flange or flanges 17 which serve as a support and the base 16 also being provided with reinforcing and supporting members 18 and 19.

Disposed at the rear of the front member 10 and secured thereto at 20 by welding, soldering or other means, there is a horizontal member 21 which has its ends 22 secured to the sides 11 of the front member 10 and its middle portion secured to the upper portions of the sides 14 and the back 15 of the fireplace opening 13. As will best be seen by referring to Figures 2 and 3, the horizontal member 21 is provided with a rearwardly depending flange 21', a portion of which is cut and is disposed at the inner side by the back member 15 to which it is secured. It will be understood that, with this construction, the fireplace opening 13 is complete, for its bottom is at the base 16, its sides at the sides 14, its back at the back 15 of the fireplace and its top is formed by the horizontal member 21. It will also be understood that, with this construction, the sides 14 of the fireplace opening are reinforced and are held relatively to the sides 11 which ex-

tend rearwardly from the front member 10. As an additional means of holding the members of the fireplace opening rigid, a brace 23 is provided having flanges 24 which are secured to the rear 5 of the back 15 by welding, soldering, or other means, the brace 23 having its ends secured to the sides 11 and to the flanges 12 by welding, soldering, or other means.

Disposed above the horizontal portion 21 there 10 is a hollow, bent reinforcing member 25 which has flanges 26 which are secured to the rear of the front member 10 by welding, soldering, or other means. Above this reinforcing member 25 and at the corners of the fireplace, there are 15 triangular reinforcing members 27 which have their sides secured to the front member 10 and to its sides 11 by welding, soldering, or other means. Above the said triangular reinforcing members 27 there is disposed at the rear of the 20 front member a horizontally extending reinforcing member 28 which is angular in cross section and which has flanges 29 secured to the rear of the front member 10 by welding, soldering, or other means.

25 A metal mantel 30 is provided for the fireplace, this metal mantel having a horizontal shelf portion 31 and the mantel at the front of the horizontal shelf portion 31 extending downwardly and inwardly at 32 and having a portion 33 disposed at the outer surface of the front member 10, forming one side of a recess, the recess being formed by the metal of which the mantel 30 is 30 constructed which extends inwardly and downwardly at 34. In this recess, which is shown at 35 the front of the mantel in Figure 3 of the drawings and at the sides of the mantel in Figure 2, is disposed the top of the front member 10 and the top of the sides 11, the recesses at the sides of the mantel being a continuation of the recess 40 at the front of the mantel. The mantel at its recess or recesses 34 is secured to the front member 10 and its sides 11 by welding, soldering, or other means. Secured to the underside of the shelf portion 31 at 35 there is a member 36 which 45 extends downwardly and is secured to the front of the mantel at the inner side of its recess 34 as a means of supporting the mantel and also as a means of holding the mantel at its recess 34 in position. There are also reinforcements for 50 the mantel 30 at its sides which consist of angularly disposed metal pieces 37 which are secured to the sides of the mantel at the inner sides of its recesses at 34 and to the front of the mantel, said angularly disposed metal pieces 37 having 55 flanges 38 which are secured to the underside of the mantel shelf 31 by welding, soldering, or other means. With this construction, not only is a rigid fireplace provided which is secured to the base 16 and to which the mantel 30 is secured, 60 but this rigid, inexpensive metal fireplace is constructed and reinforced to make a permanent fireplace which may be installed in houses in the course of erection, or inserted in the wall of a room during reconstruction or remodeling.

65 It will be understood that the front member 10, together with its sides 11, may be pressed as desired to represent bricks or stone, and may be painted to give the desired effect and color.

70 Preferably the mantel is provided with a chimney member 39 which has a front member 40 and sides 41, the chimney member 39 being manufactured of sheet metal and having its sides 41 cut so that their front edges will converge with the rear of the chimney upwardly. Braces 75 42 are disposed at the rear of the front mem-

ber 40 and are secured to the front member and to its sides 41 by welding, soldering or other means. The chimney member 39 has angularly disposed reinforcing members 43 which are secured to the front member 40 and to the sides 80 41, as best shown in Figure 4 of the drawings. It will be understood that, preferably these angularly disposed reinforcing members 43, together with the base of the front member 40 and its sides 41, are secured to the shelf member 30 by welding, soldering or other means.

What is claimed is:

1. In a fireplace, a front member having an inwardly disposed portion forming a fireplace opening, a base to which the front member and its inwardly disposed portion are secured, a mantel secured to the top of the front member, and a horizontal member secured to the rear of the front member and extending from side to side of the front member and being secured to the top of the said inwardly disposed portion to form the top of the fireplace opening.

2. In a fireplace, a front member having an inwardly disposed portion forming a fireplace opening, the sides of the front member being disposed rearwardly to form the sides of the fireplace, a base to which the front member and its sides and the bottom of the inwardly disposed portion are secured, a horizontal member disposed at the rear of the front member and having its ends secured to the sides and being also secured to the front member between its sides and to the top of the inwardly disposed portion to form the top of the fireplace, and a mantel secured to the front member and to its sides.

3. In a fireplace, a front member having an inwardly disposed portion forming a fireplace opening, the sides of the front member being disposed rearwardly to form the sides of the fireplace, a base to which the front member and its sides and the bottom of the inwardly disposed portion are secured, a horizontal member disposed at the rear of the front member and having its ends secured to the sides and being also secured to the front member between its sides and to the top of the inwardly disposed portion to form the top of the fireplace, a mantel secured to the front member and to its sides, and a reinforcing member having its ends secured to the said sides and its middle portion secured to the rear of the said inwardly disposed portion.

4. In a fireplace, a front member having an inwardly disposed portion forming a fireplace opening, the sides of the front member being disposed rearwardly to form the sides of the fireplace, a base to which the bottom of the front member with its sides and the inwardly disposed portion are secured, the base having downwardly disposed supporting portions at its periphery, a reinforcing member or members secured to the bottom of the base, a member disposed at the rear of the front member and having its ends secured to the sides and being also secured to the front member between its sides and to the top of the inwardly disposed portion to form the top of the fireplace, and a mantel secured to the front member and to its sides.

5. In a fireplace, a front member having an inwardly disposed portion forming a fireplace opening and with its sides disposed rearwardly, a mantel having a shelf portion, the mantel extending downwardly and inwardly from the shelf portion and being bent to form a recess for receiving the top of the front member, and a brace secured 145 150

ing its front and sides extending downwardly and inwardly where they are mounted on the front member and its sides, and a member secured to the rear of the front member with its ends secured to the sides of the front member and with its central portion secured to the top of the said inwardly disposed portion to form the top of the fireplace.

14. In a fireplace, a front member having an inwardly disposed portion forming a fireplace opening and rearwardly disposed sides forming the sides of the fireplace, a base to which the front member with its inwardly disposed portion and its sides are secured, a hollow mantel having its front and sides extending downwardly and inwardly, where they are mounted on the front member and its sides, a member secured to the rear of the front member with its ends secured to the sides of the front member and with its central portion secured to the top of the said inwardly disposed portion to form the top of the fireplace, and a hollow chimney member secured to the top of the mantel.

15. In a fireplace, a front member having an inwardly disposed portion forming a fireplace opening and rearwardly disposed sides forming the sides of the fireplace, a base to which the front member with its inwardly disposed portion and its sides are secured, a hollow mantel having its front and sides extending downwardly and inwardly where they are mounted on the front member and its sides, a member secured to

the rear of the front member with its ends secured to the sides of the front member and with its central portion secured to the top of the said inwardly disposed portion to form the top of the fireplace, and a member secured to the rear of the said inwardly disposed portion and with its ends secured to the sides of the front member.

16. In a fireplace, a front member having an inwardly disposed portion forming a fireplace opening, the sides of the front member being disposed rearwardly to form the sides of the fireplace, a base to which the front member and its sides and the bottom of the inwardly disposed portion are secured, a horizontal member secured to the top of the inwardly disposed portion to form the top of the fireplace opening, a mantel secured to the front member and to its sides, and a reinforcing member having its ends secured to the sides of the front member and its middle portion secured to the rear of the said inwardly disposed portion.

17. In a fireplace, a front member having an inwardly disposed portion forming a fireplace opening and with its sides disposed rearwardly, a mantel having a shelf portion and being bent to form a recess for receiving the top of the front member, and a brace secured to the underside of the shelf portion and to the mantel at the inner side of the recess.
